UNITED STATES PATENT OFFICE

147,585

DESIGN FOR A TOY DOG

Elisabeth P. Hall, Westwood, Mass., assignor to National Fireworks, Inc., Hanover, Mass., a corporation of Massachusetts

Application December 11, 1946, Serial No. 135,407

Term of patent 14 years

(Cl. D34—2)

To all whom it may concern:

Be it known that I, Elisabeth P. Hall, a citizen of the United States, residing at Westwood, in the county of Norfolk and Commonwealth of Massachusetts, have invented a new, original, and ornamental Design for Toy Dogs, of which the following is a specification, reference being had to the accompanying drawings, forming a part thereof.

In the drawings:

Fig. 1 is a front view of a toy dog showing my new design;

Fig. 2 is a three quarter perspective view of the toy dog as seen from an elevated viewpoint;

Figs. 3 and 4 are, respectively, a left hand side view and a right hand side view of the toy dog.

I claim:

The ornamental design for a toy dog, as shown.
ELISABETH P. HALL.
